UNITED STATES PATENT OFFICE.

HENRY M. ZIMMERMAN AND THEODORE N. CLUTE, OF WASHINGTON,
DISTRICT OF COLUMBIA.

COMBINED FOOT-REST AND BOOT-JACK.

SPECIFICATION forming part of Letters Patent No. 228,581, dated June 8, 1880.

Application filed April 14, 1880. (Model.)

To all whom it may concern:

Be it known that we, HENRY M. ZIMMERMAN and THEODORE N. CLUTE, citizens of the United States, residing at Washington, 5 in the District of Columbia, have invented new and useful Improvements in a Combined Folding Foot-Rest and Boot-Jack, of which the following is a specification.

This invention relates to a combined folding foot-rest and boot-jack.

The object of our invention is to provide a handy article, which may be folded into compact form and small space for stowing away, and which is capable of convenient attachment 15 to and use in connection with a chair as a foot-rest while the occupant ties or unties or brushes the shoes, adjusts stockings, garters, or gaiters, or dries the feet after bathing, and which may be readily attached and used separately as a boot-jack.

To this end our invention consists of a device constructed in two pieces or parts, of suitable material, hinged together at one end, the free end of one part being provided with 25 hooks, by means of which it may be temporarily secured to the rounds of a chair or other seat to form a foot-rest for the same, while the other part may be arranged to form a support for the end of said foot-rest, and which article is 30 also adapted for use as a boot-jack.

The supporting-piece is formed with a crotch or recess at its free end, and provided intermediate with a folding prop, by means of which the parts of the device may be held 35 apart at an angle, so as to adapt the device to serve as a boot-jack, as more fully hereinafter specified.

In the drawings, Figure 1 represents a perspective of our device attached to a chair, so 40 as to form a foot-rest for the same. Fig. 2 is a perspective view of the device with the parts in position to adapt it to use as a boot-jack. Fig. 3 is a longitudinal section of the implement as folded when out of use.

45 Referring to the drawings, the letter A indicates a rectangular piece of wood, metal, or other suitable material of proper length and width—say of the length and width of the average human foot. The said piece A is pref-

erably covered with a cushion, B, of carpeting or other material to form a comfortable rest for the foot. To the under side of said piece, near one end, is hinged a piece, C, of wood, metal, or other suitable material of a width approximating the width of the first- 50 mentioned piece A, and nearly equal to the same in length. The two parts are hinged together at their ends, so that when opened out and the lower edge of the part C is rested on the floor the said part C will form a substantial support for the end of the part A, when the hooks *a*, at the opposite end of said part A, are secured to the round of a chair or seat, so as to form a foot-rest for the same.

The part B, at its free end, is formed with 55 a crotch or recess, D; and it is also provided with a folding hinged prop, E, which when the parts are in a normal position sets in an opening or recess, F, in the part B, but when the device is to be employed as a boot-jack 60 can be placed, as shown in Fig. 2, so as to hold the parts from each other at an angle and present the crotch of part C in proper position to seize the heel of a boot or shoe.

In the drawings we have illustrated the 65 hooks *a* as attached to the under side of the board or support A by means of screws or nails; but in lieu of such it will be manifest that such hooks can be otherwise attached—as, for instance, the hook may have a screw- 70 threaded shank and be screwed directly into the end of the board or into a metal socket set therein.

What we claim is—

1. As a new article of manufacture, a foot- 75 rest constructed in two parts hinged together, one of said parts being provided with hooks, by means of which it may be secured to the rounds of a chair or seat, and the other adapted to serve as a support for the first-mentioned 80 part, and adapted for use as a boot-jack, all constructed substantially as specified.

2. As a new article of manufacture for household and other purposes, a combined foot-rest and boot-jack constructed in two parts hinged 90 together, one of said parts being provided with hooks, by means of which it can be secured to the round of a chair or seat to form 95

a foot-rest for the same, and the other with a crotch and an adjustable bearing, by means of which the device may be arranged to serve as a boot-jack, substantially as specified.

5 3. The combined foot-rest and boot-jack composed of the part A, provided with the hooks a, and the hinged part C, having the crotch at its free end, and provided intermediate with the folding prop E, substantially as described.

In testimony whereof we have hereunto set our hands in the presence of two subscribing witnesses.

HENRY M. ZIMMERMAN.
THEO. N. CLUTE.
